UNITED STATES PATENT OFFICE

ALBERT P. SACHS, OF NEW YORK, N. Y., ASSIGNOR TO PETROLEUM CONVERSION CORPORATION, OF NEW YORK, N. Y., A CORPORATION OF DELAWARE

PROCESS OF CONVERTING OILS

Application filed April 17, 1928. Serial No. 270,631.

The present invention relates to a process of converting hydrocarbon oils, for example those of petroleum origin, into compounds having a predominantly lower molecular weight and particularly those compounds within the gasoline range. In the system of conversion to which my invention is particularly adapted, the conversion is brought about in the vapor phase, the oil material being previously vaporized and then mingled with a gaseous carrier usually of hydrocarbon origin, which is heated to the proper temperature and is of sufficient quantity to carry out the desired reaction.

The present invention is particularly concerned with the manner of applying the carrier gas to the body of vapor undergoing conversion whereby a more efficient heating of the oil vapors is obtained. Prior to my discovery it has been the practice to mingle the carrier gas and vapor to be converted in one operation, a sufficiently long path for the mixture being provided to give the necessary time for cracking. I have now discovered that a more efficient mixing and heating will be had by mingling the carrier gas in stages whereby the vapor to be cracked is maintained over a longer course at a higher average temperature. In other words the temperature of the vapors undergoing cracking is raised as soon as such temperature has dropped a predetermined amount, thus maintaining a more uniform temperature over a longer time interval and producing a greater yield of the cracked material sought.

According to one method of carrying out my invention, I mingle one-half the quantity of oil vapor (with reference to the amount which would have been used with a given quantity of carrier gas) with one-half the available carrier gas in one stage, then at a second stage in the travel of the mixture, I introduce an additional quarter of the carrier gas, and finally at a third point, the remaining quarter of the carrier gas is introduced. Preferably, though not necessarily, a separate chamber is provided for each stage. In this manner, while a less quantity of oil vapor is treated per cubic foot of car-

rier gas, the average temperature to which the vapor is raised is greater over the same period of time, thereby resulting in a higher yield of the cracked products per pound of oil vapor treated. Moreover while a higher exit temperature of the products is had, a greater amount of heat is available for transfer to other products destined for the reaction chambers so that a substantial portion of this additional heat is recovered.

In the accompanying drawing, I have illustrated more or less diagrammatically, an apparatus for carrying out the invention as described in the foregoing.

In said drawing, reaction chamber No. 1 is supplied with vapor from a still 10 through a pipe 11 having a control valve 12, such vapor preferably having been produced in said still without having undergone an appreciable amount of cracking. Also supplied to reaction chamber 1 through a main B is a carrier gas of the desired temperature, and in sufficient amount to provide the desired number of heat units from a heating element 14 preferably in the form of a regenerative heater or hot blast stove, the gas having been passed therethrough from a holder 15. For sake of example the temperature of the carrier gas may be taken as 1400 degrees and that of the oil vapor 650 degrees F. the temperature being regulated by means of valve 15a in the offtake to chamber No. 1. The oil vapor coming in contact with the heated gaseous carrier is raised in temperature to say 1050 degrees F. which may be taken as a desirable upper limit of the conversion range, the exit temperature from the first reaction chamber being in the neighborhood of 990 degrees F. The products from reaction chamber No. 1 are now by means of pipe 16 brought into reaction chamber No. 2 wherein a further quantity of carrier gas controlled by valve 16a is introduced equal, preferably, to one-half the remainder or one-quarter of the total quantity of gaseous carrier, this having the effect of raising the temperature of the products from say 990 degrees F. to 1030 degrees F. The mixture passing out of the second reaction chamber is conducted through pipe 17 to a third reaction chamber No. 3, wherein the

mixture is subjected to the remaining quarter of the carrier gas from the stove 14 and introduced through valve 17a. In this chamber the temperature of the gases which may have fallen to around 970 degrees is raised to 1035 degrees, the exit temperature of the gases from reaction chamber No. 3 being say in the neighborhood of 975 degrees.

The final mixture leaving reaction chamber 3 may now be passed through a pipe 20 to the usual heat exchangers, rectifying and condensing columns in the last of which the gasoline-like products are recovered. Since the above-mentioned elements form no part of the present invention they have not been illustrated.

It will be understood that the temperatures given are illustrative only and that they are not to be construed as limitations, as such temperatures will naturally vary depending upon the nature of the oil undergoing conversion as well as the character of the products desired. Furthermore different proportions of the carrier gas may be used at the different stages and the number of the latter may be varied as desired. Furthermore it is not imperative that separate chambers be employed at each stage so long as the proper time element is allowed therefor and provided that means are afforded for the partially cooled reaction mixture to be properly mixed with the additional reheating gas which may be introduced at any point in the travel of the reacting mixture.

35 What I claim is:

1. In the process of converting oils in the vapor phase by mingling the oil vapor with a heated carrier gas of such quantity and temperature as to bring about the conversion reaction, the steps which consists in first subjecting the oil to be converted to vaporizing conditions in a vaporizing zone, separating the produced vapor from the unvaporized liquid, adding in stages in a reaction zone such carrier gas to oil vapor derived from said vaporizing zone and so proportioning the gas to the vapor in the first stage as to raise the temperature of said vapor to substantially that of the desired conversion temperature in excess of 900° F., allowing said reaction to take place over an applicable time interval, then adding in a second stage but before the temperature of the reacting mixture has dropped a predetermined amount, a further quantity of said carrier gas at substantially the same temperature as that added in said first stage and in sufficient quantity to raise the temperature of said mixture to substantially said original reaction temperature.

60 2. The process according to the preceding claim, in which the predetermined temperature drop mentioned is not substantially greater than 100° F.

65 3. The process according to claim 1, in which the predetermined temperature drop

mentioned is not substantially greater than 100° F., and in which more than two stages are provided, approximately one-half the total quantity of carrier gas being added in the first stage and the remainder of said gas divided substantially equally among the remaining stages.

4. The process according to claim 1, in which the initial temperature of the gas and vapor mixture is approximately 1000° F., and in which the temperature drop mentioned is not substantially greater than 100° F.

In testimony whereof I have affixed my signature to this specification.

CERTIFICATE OF CORRECTION.

Patent No. 1,842,321.

January 19, 1932.

ALBERT P. SACHS.

It is hereby certified that error appears in the printed specification of the above numbered patent requiring correction as follows: Page 2, line 51, claim 1, for "applicable" read appreciable; and that the said Letters Patent should be read with this correction therein that the same may conform to the record of the case in the Patent Office.

Signed and sealed this 29th day of November, A. D. 1932.
